UNITED STATES PATENT OFFICE

IRVIN F. DITTMAR, OF WILLIAMSPORT, PENNSYLVANIA, ASSIGNOR TO THE CROMAR CO.,
OF WILLIAMSPORT, PENNSYLVANIA, A CORPORATION OF PENNSYLVANIA

MACHINE FOR COATING STRIPS OF LUMBER

Application filed December 7, 1928. Serial No. 324,349.

My invention relates to improvements in strip finishing machines.

The object of my invention is to provide an improved construction of filler receptacle, whereby the filler will be forced by the pressure member or agitator against the strip of flooring passing through the machine and force the filler into the pores of the wood, leaving a thin film of filler on the inner face of the strip of flooring or the like.

Another object of my invention is to provide a filler receptacle of this character having novel means for engaging the upper and lower edges of the strip of flooring and the inner face of the strip at each end of the receptacle preventing the filler from escaping around the discharge opening as the strips of flooring move rapidly past the filler receptacle.

Another object of my invention is to provide a filler receptacle of this character in which means are provided for any variation in the thickness or width of the strip so that the means for preventing the filler from escaping around the strip will at all times tightly engage the same, and at the same time providing means for taking up the wear.

A further object of my invention is to provide a filler receptacle of this character in which the several parts can be readily removed and assembled for repairs, and at the same time provide a structure which is more effective in operation and having certain details of structure and combination of parts hereinafter more fully set forth.

A still further object of my invention is to provide oscillating supports with detachable guide strips so arranged that they can be readily removed and new guide strips placed therein when they become worn.

In the accompanying drawings:—

Figure 1 is an end elevation of my improved filler receptacle.

Figure 2 is a side elevation of Figure 1.

Figure 3 is a vertical transverse sectional view taken on the line 3-3 of Figure 2.

Figure 4 is a front elevation looking in the direction of the arrow, Figure 3.

Figure 5 is a horizontal longitudinal sectional view taken on the line 5-5, Figure 4.

Figure 6 is a perspective view of the members for grinding the strips of flooring and closing the discharge opening of the filler receptacle showing the several members in their separated relation.

Figure 7 is an enlarged sectional view similar to Figure 3.

Figure 8 is a perspective view of one of the locking members for holding the several closing members in their operative position.

Figure 9 is an enlarged end view of the upper and lower blocks carrying the combined guide and closing members for the discharge opening.

Referring now to the drawings, 1 represents the filler receptacle which may be of any desired form, but preferably of the form shown, and which carries at one side a bracket 2 which extends upwardly as indicated at 3, and upon which is mounted the motor 4, by means of the brackets 5 and 6. The motor 4 has its shaft 7 extending downwardly into the receptacle 1 and has its lower end provided with the pressure member and agitator 8 which causes the filler within the receptacle to be forced outwardly towards the discharge opening 9 in the receptacle, whereby the pressure on the filler is obtained for forcing the filler against the strips as rapidly as they pass the discharge opening of the receptacle.

The construction of the agitator 8, and the adjustment of the motor, as shown in Figure 2 of the drawings, will not be fully described as they form separate inventions and are covered by application executed the 15th day of October, 1928 filed Dec. 7, 1928, Serial No. 324,350. The side of the filler receptacle 1, above the discharge opening 9, is provided with two outwardly extending rigid brackets 10 and 11 to which are fastened the two holding plates 12 and 13 by means of bolts 14 and 15. The side of the receptacle below the discharge opening 9 is provided with rigid brackets 16 and 17 to which are clamped the holding plates 18 and 19 by means of bolts 20 and 21. The member 29 at the upper end of the discharge opening 9, which engages the upper edge of the strip of flooring 23 in its passage by the discharge

opening, comprises a rectangular block 24 having a circular bore 25 extending therethrough from end to end, and said bore intersecting the lower face of the block 24, as clearly shown in Figures 7 and 9 of the drawings.

Arranged within the semi-circular base 25 of the block 24 is a cylindrical guide member 26 which has its face cut away as indicated at 27 and provided with a longitudinally rectangular groove 28 in which is arranged a metal or fiber guide strip 29 which engages the upper beveled face 30 of the strip of flooring 23, and forms a tight joint with the beveled face 30 thereof. The block 24 is cut away as indicated at 31, which cut away portion intersects the circular groove 25 in the block, and carried by the member 26 is a rigid arm 32 which extends out through the cut away portion 31 and a slot 33 in the block, and whereby the member 28 is rocked within the circular groove in the block 24 for causing the fiber contacting strip 29 to at all times engage the bevel 30 of the strip of flooring 23 to prevent the leakage of the filler around the upper edge of the strip.

Loosely connected with the outer ends of the arm 32 is a link 34 which extends upwardly and passes through the member 35 which is rotatably supported by the side of the receptacle by means of the trunnions 36 and 37 to allow the same to oscillate.

Surrounding the link 34, above the member 35, is a coil spring 38 which extends up into the housing 39, and the link 34 within the housing is screw threaded as indicated at 40, and has screwed thereon a nut 41 whereby the tension of the spring 38 may be varied for causing the proper tension of the fiber strip 29 on the beveled face 30 of the strip 23. A block 42 is arranged below the discharge opening of the receptacle 1 and has arranged therethrough a circular bore 43 in which is arranged a cylindrical guide member 44 which extends outwardly beyond the upper face of the block 42 and has its face cut away as indicated at 45. The cut away face of the cylindrical member 44 is provided with a longitudinal recess 46 in which is arranged guide strip 47 adapted to engage the beveled face 48 of the groove in the lower face of the strip of flooring 23. The block 42 is cut away as indicated at 49 and provided with a slot 50 communicating with the circular recess 43 in the block and rigidly carried by the cylindrical member 44 is a rod 51 which extends out through the slot 50, and which cut away portion 49 is provided with weights 52 and 53 adjustably held thereon by means of set screws 54 and 55, whereby the cylindrical member 44 is oscillated in the circular groove 43 so that the guide strip 47 bears against the beveled wall 48 of the groove of the strip of flooring so that the weight causes the proper

tension on said strip to prevent the leakage of the filler below the lower edge of the strip.

Supported by the filler receptacle 1 is a backing plate 56 which is adapted to engage the outer face of the strip of flooring 23 and held against outward movement. This backing plate 56 is of a width approximately that of the strip of flooring 23 so as to have a firm pressure thereon, and the backing plate 56 has secured thereto a horizontally rectangular bar 59 which is of a length less than the backing plate, and secured by means of bolts 60 and 61 see Fig. 5 are the two end plates 62 and 63. The end plates are each provided with inwardly extending arms 64 and 65 which extend over the top of the backing plate as clearly shown in Figure 6 of the drawings. The outer edges of the end plates 62 and 63 are provided with the semi-circular grooves 66 and 67.

In order to prevent the escape of the filler from the ends of the opening 9 of the filler receptacle 1, I provide the two wooden plates 68 and 69 which extend along the vertical side walls of the filler receptacle and have bifurcated outer ends 70 which are adapted to straddle the backing plate 56 on the inside of the end plates 63 and 62. The vertical walls 71 and 72 of the wooden bars 68 and 69 are adapted to engage the inner face of the strip of flooring 23 and prevent the escape of the filler from the ends of the opening 9 of the receptacle 1. The ends of the bars 68 and 69 are beveled as indicated at 73 and 74 to prevent the scratching of the strip of flooring 23 in its rapid passage through the machine. The wooden bars 68 and 69 are longitudinally movable in guides 75 and 76, arranged in the vertical side walls of the filler receptacle 1. The plates 77 and 78 are attached to the rear wall of the filler receptacle 1 by means of bolts 79 and said plates are provided with screw threaded openings 80 and 81 through which pass the thumb bolts 82 and 83 which are adapted to engage the inner vertical walls 84 and 85 of the wooden bars 68 and 69 whereby the wooden bars are moved forward in the guides 75 and 76 to cause the proper tension of the same on the inner face of the strip of flooring 23.

In order to hold the blocks 24 and 42 in position, and also to hold the backing plate 56 in its proper position, I have provided the two peculiarly shaped plates 86 and 87. These plates, as shown, have the end 88 bifurcated at 89, through which pass the bolts 14 and 15, which is screwed into the brackets 10 and 11 rigidly carried by the front edge of the receptacle 1, on the outside of the plates 86 and 87, and the plates 12 and 13 which extend down and engage the ends of the side plates 62 and 63 of the backing plate 56, whereby said backing plate is rigidly held in the position shown in Figure 7

of the drawings. The downwardly extending portions 94 and 95 of the plates 86 and 87 engage the outer face of the block 24 and hold it against outward movement, and the portions 96 and 97 of the members 86 and 87 extend over the upper face of the block 24 and prevent the upward movement in respect to the receptacle. The blocks 98 and 99 are shaped and arranged exactly the same as the blocks 86 and 87 and engage the backing plate 56 and the block 42 in the same manner, and are held against outward and vertical movement. The blocks 98 and 99 are held in position by the plates 18 and 19 fully described in the first part of this specification.

The filling receptacle is provided with openings in its side walls normally closed by plates 68 and 69 so that the agitator 8 can be inspected or to allow the receptacle to be cleaned. The side walls are provided with suitable guideways to receive sheet metal plates to close the openings so that the plates 68 and 69 can be removed without allowing the filler in the receptacle to run out. The guide strips 47 and 48 can be formed of metal, wood, fiber or any other suitable material and in some instances I have formed the strips 47 of steel and strips 30 47² of fiber, in which case I form the strips 29 of fiber. The strip 47 is provided with grooves 47' at its corners to receive the pointed edges of the strips of flooring in order to form a tight guiding surface for the lower 35 edge of the strip in its passage by the receptacle. By forming the strip 47 rectangular in cross section and providing the grooves in the corners, the strip can be removed and turned so as to bring a new guiding surface into position as the grooves wear out, whereby four guiding surfaces are provided in each strip.

In order to limit the oscillation of the cylinder member 44, I provide the block 42 45 with a set screw A adapted to be engaged by a nut 51 whereby the guiding strips are held in their proper position to receive the grooved edges of the flooring strip.

In the specification and claims I have used 50 the term "semi-liquid" to cover the use of materials such as filler, paste, wax, glue, emulsion, etc., and I do not wish to limit myself to the application of any particular kind of material in my apparatus as I am aware that it is capable of applying various kinds of material to a strip in its passage therethrough and while I have described a machine particularly adapted for applying a filler to a strip of flooring, the 55 machine is capable of applying other materials to various other strips of material.

Having thus fully described my invention what I claim is:

1. A semi-liquid applying receptacle for machines of the character described com-

prising a receptacle having a discharge opening in one side thereof, detachable supporting blocks secured to the receptacle around the discharge opening and oscillating guide members carried by the blocks.

2. A semi-liquid applying receptacle for machines of the character described comprising a receptacle having a discharge opening in one side thereof, supporting blocks removably secured to the receptacle around the discharge opening and movable guide members within said blocks and extending beyond one face thereof.

3. A semi-liquid applying receptacle for machines of the character described comprising a receptacle having a discharge opening in one side thereof, removable supporting blocks carried by the receptacle above and below the opening, and guide members carried by the blocks and extending across said opening.

4. A semi-liquid applying receptacle for machines of the character described comprising a receptacle having a discharge opening in one side thereof, removable supporting blocks carried by the side of the receptacle above and below the opening, movable guide members within the blocks and extending across the upper and lower edges of said opening.

5. A semi-liquid applying receptacle for machines of the character described comprising a receptacle having a discharge opening in one side thereof, removable supporting blocks carried by the side of the receptacle above and below the opening, oscillating guide members arranged within the blocks and extending beyond one face thereof across the upper and lower edges of said opening.

6. A semi-liquid applying receptacle for machines of the character described comprising a receptacle having a discharge opening in one side thereof, removable supporting blocks extending across the outer face of the receptacle above and below the discharge opening and having circular openings therethrough intersecting one wall of the block, and oscillating guide members mounted in said opening and extending across the upper and lower edges of the discharge opening.

7. A semi-liquid applying receptacle for machines of the character described comprising a receptacle having a discharge opening in one side thereof, supporting blocks extending across the outer face of the receptacle above and below the opening and having openings therethrough intersecting the upper and lower faces of the block, oscillating guide members within said opening and extending inwardly over the upper and lower edges of the discharge opening.

8. A semi-liquid applying receptacle for machines of the character described comprising a receptacle having a discharge open-

ing in one side thereof, removable supporting blocks carried by the side of the receptacle above and below the opening, oscillating guide members within the said supporting blocks and extending over the upper and lower edges of the discharge opening, and blocks carried by the ends of the receptacle for engaging the inner face of the strip of material passing across said discharge opening.

9. A semi-liquid applying receptacle for machines of the character described comprising a receptacle having a discharge opening in one side thereof, removable supporting blocks carried by said receptacle around the opening, oscillating guide members arranged in the upper and lower blocks and extending across the upper and lower edges of the opening, and means for causing the tension on the guide members to cause the oscillation thereof, whereby pressure on the strip being acted upon is obtained.

10. A semi-liquid applying receptacle for machines of the character described comprising a receptacle having a discharge opening in one side thereof, oscillating guide members, arranged at the upper and lower ends of the opening, a backing plate between said movable guide members and plates at the ends of said opening and having bifurcated ends straddling the backing plate.

11. A semi-liquid applying receptacle for machines of the character described comprising a receptacle having a discharge opening in one side thereof, movable guide members arranged at the upper and lower ends of said opening, a backing plate between the movable guide members, and horizontally adjustable plates at the ends of the openings and having bifurcated ends straddling the backing plate.

12. A semi-liquid applying receptacle for machines of the character described comprising a receptacle having a discharge opening in one side thereof, guide members at the upper and lower ends of said openings, a backing plate between the guide members, movable plates at the ends of the openings and having bifurcated ends straddling the backing plate, and members carried by the backing plate adapted to guide the movable plates.

13. A semi-liquid applying receptacle for machines of the character described comprising a receptacle having a discharge opening in one side thereof, blocks secured to the receptacle at the upper and lower ends of the opening, movable guide members carried by the blocks, a backing plate between the movable guide members, movable plates at the ends of the openings and having bifurcated ends straddling the backing plate, and transverse members adapted to guide the movable plates at the ends of the openings.

14. A semi-liquid applying receptacle for

machines of the character described comprising a receptacle having a discharge opening in one side thereof, removable blocks carried by the side of the receptacle above and below the opening, oscillating guide members within said blocks and extending over the upper and lower edges of the discharge opening, a backing plate between said guide members, and plates carried by the ends of the receptacle and having bifurcated ends for straddling the inner face of the strip of material passing across the discharge opening and also straddling the backing plate and said backing plate having transverse members guiding the plates.

15. A semi-liquid applying receptacle for machines of the character described comprising a receptacle having a discharge opening in one side thereof, removable blocks carried by the side of the receptacle above and below the opening, a backing plate between the removable blocks and supporting the same, oscillating members within said blocks and extending over the upper and lower edges of the discharge opening, and plates carried by the ends of the receptacle for engaging the inner face of the strip of material passing over said discharge opening, and having bifurcated ends straddling the strip of material and the backing plate and said backing plate having transverse guides for guiding the plates at the ends of the opening.

16. The combination with a receptacle having a discharge opening, of an oscillating guide member mounted above and below said opening, and a strip guiding member detachably mounted in each of said guide members.

17. The combination with a receptacle having a discharge opening, of an oscillating guide member mounted above and below said opening, means for exerting a tension on said oscillating support, and a strip guiding member detachably mounted in each of said guide members.

18. The combination with a receptacle having a discharge opening, of an oscillating guide member mounted above and below said opening, a separate tension means for each of said oscillating supports, and a strip guiding member detachably mounted in each of said guide members.

19. The combination with a receptacle having a discharge opening, of an oscillating guide member removably mounted above and below said opening, and a strip guiding member detachably mounted in each of said guide members.

20. The combination with a receptacle having a discharge opening, of an oscillating guide member removably mounted above and below said opening, a separate tension means for oscillating said supports, and a strip guiding member detachably mounted in each of said guide members.

21. The combination with a receptacle having a discharge opening, of a block above and below said opening, an oscillating member removably mounted in each of said blocks, and a strip guiding member detachably mounted in each of said oscillating members.

22. The combination with a receptacle having a discharge opening, of a block above and below said opening, an oscillating member in each of said blocks, a separate tension means for oscillating each of said members, and a strip guiding member detachably mounted in each of said oscillating members.

23. The combination with a receptacle having a discharge opening, a block mounted above and below said opening, a removably oscillating member mounted in each of said blocks, a separate tension means for oscillating said members, and a strip guiding member detachably mounted in each of said oscillating members.

In testimony whereof I hereunto affix my signature.

IRVIN F. DITTMAR.
